CLAIM

The ornamental design for a control pod, as shown and described.

DESCRIPTION

FIG. 1 is a front, right, top isometric view of the control pod;
 FIG. 2 is a front elevation view of the control pod;
 FIG. 3 is a rear elevation view of the control pod;
 FIG. 4 is a left side view of the control pod;
 FIG. 5 is a right side view of the control pod;
 FIG. 6 is a top plan view of the control pod; and,
 FIG. 7 is a bottom plan view of the control pod.

In the drawing views the broken lines depict portions of the control pod which form no part of the claimed design.
